UNITED STATES PATENT OFFICE

104,154

DESIGN FOR A POSTURE CHAIR

Niels Yde Andersen, Kenmore, N. Y., assignor to Remington Rand, Inc., Buffalo, N. Y.

Application January 28, 1937, Serial No. 67,323

Term of patent 7 years

To all whom it may concern:

Be it known that I, Niels Yde Andersen, a citizen of the United States, residing at Kenmore, in the county of Erie and State of New York, have invented a new, original, and ornamental Design for a Posture Chair, of which the following is a specification, reference being had to the accompanying drawing, forming part thereof.

The figure is a perspective view of the posture chair, showing my new design.

I claim:

The ornamental design for a posture chair, as shown.

NIELS YDE ANDERSEN.
